(57) **CLAIM**

The ornamental design for a electronic device cover with detachable strap, as shown and described.

DESCRIPTION

FIG. 1 is a top, rear perspective view of a electronic device cover with detachable strap showing the strap in a latched configuration;

FIG. 2 is a rear elevation view thereof;

FIG. 3 is a front elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a top, front perspective view thereof; and,

FIG. 9 is a top, rear perspective view of the electronic device cover with detachable strap showing the strap in an unlatched configuration.

The electronic device cover with detachable strap is shown with a symbolic break in its height. The appearance of any portion of the article between the break lines forms no part of the claimed design. The electronic device and features of the cover shown in broken lines are environmental subject matter only that form no part of the claimed design.
